SWINGING CONVEYER MECHANISM

Augustus J. Penote, Shaker Heights, Ohio

Original application, June 6, 1927, Serial No. 196,745. Divided and this application June 15, 1931. Serial No. 544,413.

4 Claims. (Cl. 198—118)

This invention relates to swinging conveyer mechanism, the present application being a division of my application Serial No. 196,745, filed June 6, 1927, issued January 19, 1932 as patent No. 1,842,193, and especially to such conveyers mounted upon trenchers, it being a particular object of my invention to improve the type of excavating machines which include in their structure a conveyer mechanism mounted above the power mechanism for receiving thereon the excavated material from the excavating unit, so that the said conveyer is designed to deliver the material beyond the outline of the machine as a whole.

It is a further object of my invention to provide a conveyer unit above the engine of the machine and beneath the upper end of the excavating unit so that the latter may deposit its material upon the conveyer. It is also my purpose to mount the said conveyer upon pivotal means permitting swinging the said conveyer in a horizontal plane, for the purpose of depositing the material therefrom in a wide range of area forward of and at either side of the machine, as may be most convenient.

It is a further object of my invention to mount the said conveyer of the endless type, upon a vertical pivot and utilize a vertical drive shaft for the conveyer belt, as the axis for swinging the conveyer unit as above explained. It is further explained as a feature of this invention, that a single source of power, here shown as an internal combustion engine, may by various connections, serve to either drive the conveyer belt, the chain excavator, the tractor mechanism, or to adjust the vertical position of the excavator unit or the lateral position of the conveyer unit.

A still further object of my invention is to so mount the conveyer beneath the delivery end of the excavator that the entire conveyer unit, including its intermediate driving means, may be shifted longitudinal of the machine without breaking the driving connection with the power source. This arrangement of the relative position of the conveyer unit makes possible the shifting of the conveyer forwardly, as the excavator delivery end shifts in the same direction correspondingly. This is regarded as a very important feature of my invention.

With the above and other objects in view, my invention consists in the novel features of construction, combination and arrangement of parts to be hereinafter more fully described, re-

cited in the appended claims and illustrated in the accompanying drawings, in which,—

Figure 1 is a side view in elevation of my excavating machine shown in operative position;

Figure 2 is a similar view of the machine in an inoperative position of the boom;

Figure 3 is a rear elevation of the machine with the excavating unit in operative position;

Figure 4 is a plan view of the machine with portions broken away;

Figure 5 is a vertical sectional detail view in the plane indicated by the line 5—5 of Fig. 1;

Figure 6 is a detail transverse section on the line 6—6 of Fig. 1;

Figure 7 is a detail view of the connection members between the conveyer shifter and the boom link;

Figure 8 is a detail view, partly in transverse section, of the support mechanism for the conveyer, taken in the plane indicated by the line 8—8 of Fig. 1, and

Figure 9 is a detail of the same in side elevation.

Referring in detail to the drawings, 3 designates a vehicle frame comprising the usual base 6, including the sills 7, and driven by the single pair of endless traction belts 8. Upon this base is mounted a pair of inclined masts 9, at the rear of the machine, a pair of steel braces 10 resting upon the base and serving, together with the masts, to support overhanging, horizontal and forwardly-extending support members 11 in parallel relation. A rearwardly-extending digging boom 14 supports an endless chain digger unit 15, and is hinged upon the members 11 in pivotal arrangement, so that the lower end of the boom may swing outward and upward to lift the digger from the trench.

Somewhat forward of the center of the tractor base, a block 23 is mounted fixedly on the frame at either side of the machine, and a link 20 unsupported between its ends is pivoted rearwardly at one end to the boom 14 at a point 21 intermediate the ends of the boom, and at its other end to said block 23, at either side of the machine, whereby the distance between the blocks 23 and the pivot points 21, respectively, is always uniform.

The upper sprockets 18 for driving the digger chains 16 are mounted upon a transverse shaft 24, shown very clearly in Fig. 5 of the drawings. The shaft 24 is journaled in blocks 25 which are slideable in guide slots 13, and is itself driven from a lower and parallel transverse shaft 33 through the medium of bevel gears

26 on both ends of each shaft, such gears being connected by corresponding bevel gears 29 on the ends of sectional and telescopic shafts 30 at either side of the machine. For the driving connection of these four shafts in the manner shown in Fig. 5 of the drawings, four casing heads are provided to protect the gears and to hold them in engagement. The outer sides of the blocks 25 which in a horizontal plane, are rectangular in form, are provided with vertically extending flanges 27 upon which the upper casing heads 28 are mounted. Within the lower portion of each casing 28 are located the beveled gears 29 carried by said vertical, telescopic shafts 30.

10 In the lower casings 28, the inner faces of the same engage the peripheral flanges 41 of the casing 42 which protects the shaft 33, as shown in Fig. 5. From this description, it will be seen that each of the telescopic shafts 30 may rotate bodily together with its bevel gears 29 without interrupting movement of the boom lengthwise of the machine. The shafts 30 are shown in their closed relation in Figs. 1, 3 and 5; while they are shown in their extended relation in Fig. 2 while the boom is raised and shifted forwardly. The casing 42 is divided into two tubes, two cup members 43 being riveted to the casing sections and to each other. Within this intermediate casing 43 a worm gear 45 is mounted on the shaft 33 for rotation therewith, and a worm shaft 46 enters the casing and engages the gear 45 for driving the excavating chains, and is itself driven from the main power shaft 47 by gear 48.

20 30 35 40 A very important feature of my combined machine is the provision of a conveyer just underneath the upper end of the excavating or digger unit, and so mounted that it may be swung about a vertical axis by power means, to deliver the material at different positions desired.

45 It is characteristic of the conveyer mechanism disclosed in this application that such conveyer 68 may be swung outside the outline of the machine, and in an arc extending over 180 degrees or somewhat more, depending upon the character of the surface of the ground where the conveyer may deposit such material. Such mounting of the conveyer comprises actuating means for the movement of the conveyer unit about its vertical axis and, further, power-driven means for actuating the conveyer belt itself, and such mounting will now be described.

50 55 60 65 70 Within a fixed casing 58, suitable to enclose a cylindrical hollow casing 59, I enclose driving worm gearing, and shown in vertical section in Fig. 6. The said vertical casing 59 may rotate upon suitable bearings 60, and has mounted thereon for its actuation a worm gear 61 engaged by the driving worm 62 mounted on the horizontal drive shaft 63 which protrudes through the casing 58 and is slidably and non-rotatably engaged with the worm 62 by polygonal form of the shaft in cross-section or by keying, to prevent relative rotation of the shaft and worm. Integral with the casing 59 is an upper enlarged hollow gear casing 64, preferably rectangular in outline in cross-section but somewhat elongated in a direction lengthwise of the belt.

75 Mounted on said casing 64 and rising therefrom in an upward and rearward direction are provided frame arms 65 whose upper ends are widely spaced and have bearings thereon 66 for receiving therein a horizontal drive shaft 67

upon the intermediate portion of which between the arms 65 is pivoted the spaced conveyer frame members 68 which are rigidly braced in their separated relation for supporting the conveyer belt 69 thereon and driving rolls 70, one of which is mounted on the shaft 67 and the other in bearings at the outer end of the frame members 68, the endless conveyer belt 69 being mounted conventionally on said rolls.

80 85 90 95 100 Forward of the arms 65 a pair of spaced brace members 71 are pivoted to the casing 64 in suitable manner with the upper ends thereof positioned just outside of the frame 68 on either side thereof, and adapted to engage, interchangeably, a bolt or pin on the members 68 to adjust the desired height of the conveyer on its pivot 67. Suitable means may be provided for locking the brace members in their adjusted inclination. The belt element 69 is driven from the roll 70 carried on the shaft 67, the latter having on its ends outside the arms 65, suitable sprockets 72. A driving shaft 73 passes through the gear casing 64 parallel to shaft 67 and mounted upon the side walls 74 of casing 64 in bearings therein. Sprockets 72 similar to those on shaft 67 are mounted in alinement with their corresponding gears and sprocket chains 75 at either side engage the respective sprockets.

105 110 115 120 125 130 135 140 145 150 By the structure above described, the rotation of shaft 63 may drive the casings 59 and 64 together with their supported conveyer structure 68, about the axis of the vertical casing 59, while the conveyer belt 69 may be actuated from shaft 73 while the conveyer is in any position upon said axis. For driving the shaft 73, a vertical shaft 76 is mounted within and longitudinally of the casing 59, being provided with sleeve members 77 engaging the ends 78 interiorly of the casing 59, to make proper rotation therein. Both ends of the shaft 76 are provided with bevel gears 79, the upper one of which engages a bevel gear 80 secured to the shaft 73 within the gear casing 64. A similar bevel gear 80 is mounted upon a horizontal shaft 81 for engaging gear 79 below the casing 59, so that rotation of shaft 81 will drive the conveyer belt 69.

155 160 165 170 175 180 185 190 195 200 The sleeves 77 of the shaft 76 rotate upon suitable bearings 82 upon the ends of the casing 59, so that the parts 59 and 76 are independently rotatable, the latter driving the conveyer belt, while the former adjusts the conveyer in its relative position about the axis of the shaft 76. The shaft 63 is elongated for quite an extent and is slidably movable through the worm 62 whereby the shaft is immovable lengthwise of the frame, but rotatable to drive the worm, while the entire conveyer mechanism with its gearing and casings 58, 59 and 64, are movable longitudinally of the machine as the worm 62 slides along the fixed shaft 63, these arrangements of relative parts serving an important function to be described now in further detail. It should be noted, however, that the shaft 81 is carried lengthwise of the frame together with the bevel gear 80, another portion of the shaft 81 sliding through an element for driving the same rotatably.

205 210 215 220 225 230 235 240 245 250 While the casing 58 has been referred to as "fixed", in describing the parts mounted within the same, such term is intended to be used in the sense of being fixed relative to the rotating parts within. Because of the arrangement of the boom and its chain digger mechanism thereon for movement longitudinal of the machine, it has been found necessary that the casing 58

together with all parts carried thereby, shall be mounted for corresponding longitudinal movement in parallelism with the direction of movement in which the boom travels, to insure

5 vertical alinement of the upper end of the chain 50 and plates 51, and the approximate point above the axis of the parts 59 and 76. The structure for causing such movement of the conveyer mechanism bodily forward will now be described.

10 Mounted forward of the braces 10 and the casings 58, 59 and 64, are frame braces 5 upon which the forward ends of the L's 50 and plates 51 are mounted, the rear ends of such L's and plates being mounted securely upon the long braces 10, in the manner indicated in Fig. 5 of the drawings. Between the rearward position of the plate or bar 49 which is shown in Fig. 5 of the drawings, and carries the casing 20 43 and drive gearing for the shafts 30, and the forward braces 5, the casing 58 is mounted upon said L's 50 and plates 51 for reciprocating movement thereon longitudinally of the machine.

The casing 58 is carried by vertical bars 83 which may be L-bars connected together by flat plates 84 bolted or riveted thereto, the casing 58 being directly mounted between said plates 84 which are suitably spaced to receive it, as shown in Fig. 9.

30 To the upper ends of the bars 83 are secured outwardly-directed blocks or plates 85, as shown in Fig. 8 and of proper size and proportions to fit the space between the L's 50 whereby the casing 58 and its mounting may readily travel lengthwise of the machine. Suitable inclined braces 86 connect the bars 83 and the plates 84 for the purpose of great rigidity. The casing 58 is provided at its lower position with a downwardly-extending arm 87 perforated 40 to receive therein the shaft 81, as shown in Fig. 1. To said arm 87 there is fixed a link 88 extending rearwardly and connected with actuating means for reciprocating the conveyer in the track just described.

45 When the digger mechanism 15 is in its lower or operative position in the trench, the link 20 is substantially in horizontal position, as shown in Fig. 1. This position is further shown in Fig. 7. The link 88 is then substantially parallel with link 20. A lever bar 89 is pivoted to a part 90 of the base, and the upper end of bar 89 is then pivoted to the rear end of the actuating link 88, so that swinging the lever bar 89 on its pivot will reciprocate the casing 58 along the parts 50 and 51, and as a result, when the digger mechanism 15 moves toward or from the trench being dug, the long link 20 will move on its pivot 23, and the casing 58—59—64, together with the conveyer supported thereby, will be moved bodily lengthwise of the machine to cause the position of the conveyer to remain beneath the delivery end of the endless chain digger.

50 It is to be noted that the parts 20 and 89 are not connected directly together, though the former operates the latter. Instead, an inclined link or brace 91 connects the two, so that the fulcrum of the bar 89 may remain constant in position, while the digger boom is swinging 55 the bar 89 and thence the casing 58. The movement of the latter, which carries with it the conveyer itself as well as its actuating mechanism, is guided positively by the horizontal travel of the blocks 85 in the tracks resulting from 60 the L's 50 and plates 51. The travel is in the

longitudinal direction of the machine, and serves to attain the above-named result as to the relative position of the conveyer and the digger mechanism.

65 The movement of this casing 58 carrying with it the conveyer itself is a great advantage since it permits the bodily movement of the shaft 24 in the slot 13 and yet maintains a substantial position of the said shaft directly over the conveyer belt, such relative position of the parts not varying materially while the digger mechanism reaches the ground.

70 The movement of the two elements—the boom and the delivery conveyer 68, in unison longitudinally of the machine frame, makes feasible the swinging of the conveyer 68 about the vertical shaft 76 to deliver the material either forward of the machine or at either side thereof, the adjustment of the conveyer on the tracks at 75 as the digger mechanism rises, insuring the dropping of the material at all times upon the substantially identical spot on the conveyer apron 69.

80 The drive shaft 47 is the main power shaft. It is longitudinal of the machine and extends rearwardly from the engine 4 and has various driving connections with the several elements of the machine. It has suitable gear connection 85 with the worm shaft 46, sprocket drive connection 96 with the worm shaft 63 and other drive connection 97 with the shaft 81 positively keyed to the bevel gear 80. Shaft 47 drives the tractor belts 8 by worm and gear which drive cross shafts 93 having sprockets 94 at their ends,

85 each driving a chain 95, as shown in Figs. 1 and 100 2. Not all the details of the selective drive mechanism for furnishing power for the several parts of the machine are illustrated in associated relation, since these features follow more or less, the structure disclosed in my former Patent No. 115

1,553,833 issued Sept. 15, 1925 whose transmission gearing is substantially like that of the present disclosure. Such reference is made because no claim is made herein to such driving features.

110 120 Operation.—The conveyer 68 has two power-actuated movements—driving of the shaft 63 from the engine shaft 47 through the intermediary of the sprocket chain 96 whereby the entire conveyer unit is swung about the axis of the vertical shaft 76 to deliver material from the conveyer beyond the outline of the machine on either side of or in front of the said shaft 76, and driving of apron rolls 70 through the actuation of the chains 75, bevel gears 79 and 80, shaft 125 76 and the horizontal shaft 81 which receives its power from the engine shaft 47 by the driving connection 97. This latter actuation of the conveyer apron 69 may be attained when the conveyer unit is adjusted to any one of its relative positions about the axis of shaft 76.

130 The connection of the boom 14 with the conveyer unit 69 by the link system shown in Fig. 7 of the drawings, makes the mutual movement of the two elements very positive and certain, so that the point upon the apron 69 directly above the shaft 76 will remain substantially beneath the upper end of the digger unit 15 during the position of the lower end of the unit 15 in the trench. Some time after the said lower end of the unit 15 has moved out of the trench, a point will be reached where the shaft 24 has moved forward in the machine faster than the vertical shaft 76 of the conveyer mechanism has been advanced by its connection with 140 145 150

the link 20, but it is now immaterial what the relative position of the two units 15 and 69 is, since the unit 15 is no longer carrying material from the trench, and hence is not delivering anything at points beneath the shaft 24. When, however, the rear end of the digger unit 15 is again lowered as far as or below the ground surface, the shaft 24 will have moved back to a position above the conveyer unit 69 as before.

10 The purpose of holding the boom in horizontal position as shown in Fig. 2 is to provide a practical position which may be used, though not essential, for transportation, especially over highways, one means for moving the boom 15 downwardly and rearwardly to the operative position, includes the winding reels 52 which are unwound when the unit 15 sinks downwardly. Thus the two units 15 and 69 are actuated together from a common source of power, but they 20 are adjusted together in proper relative position while it is essential that they should be, when the unit 15 is of the structural form shown in these drawings.

Having now fully described my invention, 25 what I claim as new and desire to secure by Letters Patent is:

1. An endless conveyer having at one end a supporting frame including a hollow non-rotatable casing, an elongated main frame upon 30 which said supporting frame is movable, a vertically elongated hollow casing rotatably mounted upon a vertical axis in said non-rotatable casing, means rigidly secured to said rotatable casing for mounting said conveyer thereon, a 35 vertical drive shaft mounted axially within said rotatable casing, two power driven shafts mounted longitudinally of said main frame, one extending through the non-rotatable casing and having gear connections within the latter for 40 actuating said rotatable casing and the other having at one end driving connections with said vertical shaft outside the casings, driving connections between said vertical shaft and the conveyer, the power driven shafts operating independently, so that one may swing the rotatable 45 casing and the conveyer together on its vertical axis, and the other may drive the conveyer while in any position of said rotatable casing.

2. An endless conveyer having a supporting 50 frame including a hollow non-rotatable gear casing at one end of said conveyer, an elongated main frame upon which said supporting frame is movable, a vertically elongated hollow casing rotatably mounted upon its vertical axis 55 within said gear casing, means rigidly secured to said rotatably mounted casing for mounting said conveyer thereon, means operating through the said vertical axis of said rotatable casing for actuating said conveyer, and including in- 60 dependent power driven shafts having separate

gear connections, one with a gear within said gear casing for actuating said vertical casing on its axis, and the other having driving connections between said conveyer and the operating means through said vertical axis, said driving connections being outside the casings, whereby one of said shafts may swing the rotatable casing and its conveyer together on its vertical axis, and the other may drive the conveyer while in any adjusted position of said rotatable casing. 80 85

3. An endless conveyer and a supporting frame therefor including a hollow non-rotatable casing, a vertically elongated hollow casing mounted in said non-rotatable casing for rotation upon a vertical axis, means for mounting the conveyer 90 pivotally upon said rotatable casing including a horizontal shaft upon which the conveyer may be adjusted in a vertical plane, a horizontal shaft extending through the upper portion of said rotatable casing, driving connections between said horizontal shafts, a vertical drive shaft mounted in bearings within said rotatable casing and having driving connections with said second horizontal shaft, means for driving the conveyer from its pivotal shaft, and bearings 100 between the two casings whereby the conveyer including its supporting and driving means may be rotated about said vertical shaft, there being actuating connections within the outer casing 105 engaging the inner casing for swinging the conveyer in a horizontal plane.

4. An endless conveyer and a supporting frame therefor including a hollow, non-rotatable casing, a vertically elongated, hollow casing mounted in said non-rotatable casing for rotation upon a vertical axis, a pair of upturned and spaced arms mounted upon the upper portion of said rotatable casing and having bearings in their upper ends, and a horizontal shaft mounted in said bearings and upon which the conveyer is pivoted in a vertical plane at one end and another pair of arms extending upwardly from said upper portion and adjustably connected to the lateral portions of the conveyer to determine the inclination of the same, a transverse horizontal shaft extending through the upper portion of said casing, driving connections between said horizontal shafts, a vertical drive shaft mounted in bearings within said rotatable casing and having at its ends driving connections for actuating the second horizontal shaft and thereby the conveyer shaft, and bearings between the two casings whereby the conveyer including its supporting and driving means may be rotated about said vertical shaft, there being 110 actuating connections within the outer casing 115 engaging the inner casing for swinging the conveyer in a horizontal plane. 120 125 130

AUGUSTUS J. PENOTE. 135
